Des. 203,340
Patented Dec. 28, 1965

203,340

MIXING APPARATUS FOR DENTAL MATERIALS

Michael W. Belde, 8824 Monogram St.,
Los Angeles County, Calif.

Filed Apr. 30, 1965, Ser. No. 85,646

Term of patent 14 years

(Cl. D24—1)

FIGURE 1 is a perspective view of mixing apparatus for dental materials showing my new design;

FIGURE 2 is an enlarged side elevation view thereof;

FIGURE 3 is an enlarged rear elevation view thereof;
and

FIGURE 4 is an enlarged top plan view thereof.

I claim:

The ornamental design for mixing apparatus for dental materials, substantially as shown.
